US00D662204S

(12) **United States Design Patent**
Franceschi et al.

(10) **Patent No.:** **US D662,204 S**
(45) **Date of Patent:** **** Jun. 19, 2012**

(54) **TARGET DEVICE**

(75) Inventors: **Francesco Franceschi**, Rome (IT);
Michael Sauer, Tuttlingen (DE); **Martin
Oberlaender**, Engen (DE); **Bodo
Kreidler**, Tuttlingen (DE); **Juergen
Bogenschuetz**, Altheim (DE)

(73) Assignee: **Karl Storz GmbH & Co. KG** (DE)

(**) Term: **14 Years**

(21) Appl. No.: **29/394,978**

(22) Filed: **Jun. 23, 2011**

(30) **Foreign Application Priority Data**

Dec. 23, 2010 (EM) 001798331-0026

(51) **LOC (9) Cl.** **24-02**

(52) **U.S. Cl.** **D24/140**

(58) **Field of Classification Search** D24/133,
D24/135, 140, 190-192; 606/96, 103, 104,
606/108, 130
